(57) **CLAIM**

The ornamental design for an ear clip, as shown and described.

DESCRIPTION

FIG. 1 is a rear perspective view of an ear clip;
 FIG. 2 is a rear elevation view of the ear clip;
 FIG. 3 is a front elevation view of the ear clip;
 FIG. 4 is left side elevation view of the ear clip
 FIG. 5 is right side elevation view of the ear clip;
 FIG. 6 is a top view of the ear clip; and
 FIG. 7 is a bottom view of the ear clip.

The broken lines represent portions of the ear clip that form no part of the claimed design. The strap is shown with symbolic breaks in its length; the appearance of any portion of the article between the break lines forms no part of the claimed design.
